EARTH MOVING DEVICE

Filed Aug. 28, 1930

FIG. 1.

FIG. 2.

FIG. 3.

INVENTOR:

RAYMOND L. HARRISON
BY Cleaver, Cox & Moore ATTYS.

UNITED STATES PATENT OFFICE

RAYMOND L. HARRISON, OF ALBUQUERQUE, NEW MEXICO

EARTH MOVING DEVICE

Application filed August 28, 1930. Serial No. 478,433.

My present invention relates to earth working apparatus and particularly to devices of the scraper type which are adapted to be drawn across the surface of the ground for the purpose of shifting earth from one position to another.

This invention is closely related to the invention set forth in my co-pending application, Serial No. 478,432, filed of even date, but differs from said co-pending application in providing new structural features.

It is one of the primary objects of my present invention to provide a new and improved hydraulically controlled mechanism for controlling the relative shifting of the draft frame of a scraper device and a tractive means such as a tractor or other suitable apparatus.

Another and more specific object of my present invention is to provide in combination with a draft frame of a device as above set forth, a hydraulic piston which is independently connected with means for shifting a bowl actuating device, and a separate shifter rod which is adapted to be directly coupled with a tractive mechanism such as a tractor.

The foregoing and other objects and advantages will be more apparent from the following detailed description when considered in connection with the accompanying drawings, wherein:

Figure 1 is a side elevational view of a device which is constructed in accordance with the teachings of my invention;

Figure 2 is a similar side elevational view disclosing a shifted position of the earth carrying bowl; and

Figure 3 is a plan view of the structure as shown in Figure 2.

Referring now to the drawings, it will be seen that I have employed like numerals to designate similar parts throughout the various figures, and in Figure 1 I have shown an earth working apparatus which includes a draft frame 10, which pivotally supports an earth receiving bowl or scraper 12. This scraper 12 is provided with a relatively sharp earth receiving edge 12^a, and is supported at each extremity upon suitable stub shafts 14.

In order to effect the rearward or counter-

clockwise tilting of the bowl 12, I provide an actuating mechanism which I have designated generally by the numeral 16. This mechanism includes a shifter member or bar 18 which is provided with an arcuate slot 20. 55 This slot 20 receives a supporting pin 22 which is carried at the upper end of a vertical support or frame 24. The rearward extremity of the shifter bar 18 pivotally supports a latch member 26, and this latch member is adapted to engage a lug 28 mounted on the periphery of the bowl 12. A trip lever 30 which is operated by exerting a longitudinal pull on a flexible connector or cord 32 serves when shifted to the right of Figure 1 60 to permit the free counter-clockwise movement of the latch member 26. A coil spring 34 continuously urges the latch member 26 in a clockwise direction.

The forward extremity of the shifter member 18 is connected to the upper end of a lever 36, which lever is pivotally carried by a pin 38 extending through an upright frame member 40. The lower extremity of the lever 36 makes a slotted connection with one extremity of a connector rod 42, the opposite extremity of said connector rod being adapted for connection with a suitable coupling 44 of a tractor (not shown). The connector rod 42 is formed in two sections, said sections 75 being connected by means of a suitable coupler 46, which serves to render said connector rod extensible. 80

A second rod 48 is pivotally connected at one extremity to the lever 36 at a point intermediate the pin 38 and the lower extremity of said lever. The opposite extremity of this rod 38 is connected to a piston 50 which is reciprocable within a cylinder 52, which cylinder is mounted on the upper side of the draft frame 10. One extremity of the cylinder 52 communicates with a tank 54 through the agency of a suitable valve 56. The opposite extremity of the cylinder 52 90 communicates with said tank through the agency of a pipe 58. The valve 56 may be opened and closed by means of a member 60 which extends between said valve and a convenient operating position, as for example, 95 from a position adjacent the seat of the trac- 100

tor (not shown). The connector or piston rod 48 is also provided with an extensible coupler 62. A heavy duty spring 64 serves as a means for continuously urging the shifter member or bar 18 to the right of Figure 1, and this spring is interposed between the upper end of the lever 36 and the tank 54. A suitable turn buckle 66 is provided for varying the tension of the spring 64. Obviously said spring may be anchored at positions other than that shown in the drawings, but for the purpose of one practical illustration I have shown the same as interposed between the upper end of the lever 15 and the tank 54.

From the foregoing it will be apparent that when the bowl 12 occupies its cutting position as shown in Figure 1 and a pulling force is exerted upon the connector rod 42 through the agency of the tractive means or tractor 20 (not shown), the cutting edge of said bowl will make a cut within the surface of the ground, providing that the valve 56 is closed. In other words, the fluid within the cylinder 25 52, which is positioned to the right of the piston 50, serves as a lock or abutment to prevent movement of said piston to the right in response to the pulling action exerted on the connecting rod 42. However, if the valve 30 56 is open and a pulling force is exerted upon the connecting rod 42, the piston 50 will be free to move to the right within the cylinder 52, thereby causing the bowl actuator mechanism 16 to be operated. In this manner the 35 actuator mechanism 16 serves to tilt the bowl 12 rearwardly, and if the valve 56 is closed at a predetermined interval, the bowl will be brought to rest at the position shown in Figure 2. However, if the valve is closed 40 at a later interval, the bowl will be shifted to a still further rearward position.

The heavy duty spring 64 acts upon the lever 36 so as to swing said lever in a clockwise direction when the valve 56 is open and the tractor or tractive means is stopped. When the actuator member 18 has been urged 45 forwardly in response to the pull of the spring 64, the bowl will be free to roll in a clockwise direction as viewed in Figures 1 and 2 when a pulling force is exerted upon the frame 10.

Having thus described my invention, what I claim as new and desire to secure by Letters Patent is:

55 1. In an earth working device adapted to be moved across the surface of the ground, a tiltable earth receiving means, a draft means for urging said earth receiving means across the surface of the ground, hydraulic mechanism adapted for connection with a suitable tractive means, said hydraulic means including a piston, a cylinder, a rod connected with said piston, and a second rod adapted to be coupled with said tractive means, and means for actuating said earth receiving

means, said hydraulic mechanism being operable in response to said actuating means.

2. In an earth working device adapted to be moved across the surface of the ground, 70 a tiltable earth receiving means, a draft means pivotally supporting said earth receiving means for urging said earth receiving means across the surface of the ground, hydraulic mechanism adapted for connection with a suitable tractive means, said hydraulic means including a piston, a cylinder, a rod connected with said piston, and a second rod adapted to be coupled with said tractive means, and means for actuating said earth receiving means, said hydraulic mechanism being operable in response to the movement of said actuating means.

3. In an earth working device adapted to be moved across the surface of the ground, 75 a tiltable earth receiving means, a draft frame for urging said earth receiving means across the surface of the ground, a hydraulic mechanism mounted on said draft frame, said mechanism including a substantially horizontally shiftable piston rod, a second substantially horizontal rod adapted to be connected with a suitable tractive means, and means for actuating said earth receiving means, said actuating means being operable in response to the actuation of said rods.

4. In an earth working device adapted to be moved across the surface of the ground, 100 a tiltable earth receiving means, a draft means for urging said earth receiving means across the surface of the ground, hydraulic mechanism adapted for connection with a suitable tractive means, said hydraulic means including a piston, a cylinder, a rod connected with said piston, and a second rod adapted to be coupled with said tractive means, means for actuating said earth receiving means, said hydraulic mechanism being operable in response to the movement of said actuating means, and resilient means for urging said actuating means in a given direction.

105 5. In an earth working device adapted to be moved across the surface of the ground, a tiltable earth receiving means, a draft means for urging said earth receiving means across the surface of the ground, hydraulic mechanism adapted for connection with a suitable tractive means, said hydraulic means including a piston, a cylinder, a rod connected with said piston, and a second rod adapted to be coupled with said tractive means, and means for actuating said earth carrying means including a pivoted member, and a shiftable actuator member, said pivoted member being connected with said hydraulic mechanism.

115 6. In an earth working device adapted to be moved across the surface of the ground, a tiltable earth receiving means, a draft means for urging said earth receiving means across the surface of the ground, hydraulic mecha-

nism adapted for connection with a suitable tractive means, said hydraulic means including a piston, a cylinder, a rod connected with said piston, and a second rod adapted to be
 5 coupled with said tractive means, means for actuating said earth carrying means including a pivoted member, and a shiftable actuator member, said pivoted member being connected with said hydraulic mechanism, and
 10 resilient means for urging said pivoted actuating member in a given direction.

7. In an earth working device adapted to be moved across the surface of the ground, a tiltable earth receiving means, a draft means
 15 for urging said earth receiving means across the surface of the ground, hydraulic mechanism adapted for connection with a tractive means, said hydraulic means including a piston, a cylinder, an extensible rod connected with said piston, and a second extensible rod adapted to be coupled with said tractive means, and means for actuating said earth receiving means, said hydraulic mechanism being operable in response to the actuation of said actuating means.

8. In an earth working device adapted to be moved across the surface of the ground, a tiltable earth carrying means having an earth receiving edge, a draft frame mechanism for urging said earth receiving means across the surface of the ground, hydraulic mechanism adapted for connection with a suitable tractive means, said hydraulic mechanism including a cylinder mounted on the upper side of said draft frame, a piston in said cylinder and means for connecting said piston with said tractive means, and means for actuating said tiltable earth receiving means, said piston being shiftable in response to the actuation of said actuating means.

9. In an earth moving device adapted to be moved across the surface of the ground, a draft frame, tiltable earth carrying means on said frame, actuating means engageable with the earth carrying means for tilting same, a hydraulic mechanism connected with said actuating means, said hydraulic mechanism being adapted for connection with a tractive means and shiftable in response to the force exerted by such tractive means, and a cam for controlling the travel of the portion of the actuating means which engages said earth carrying means.

50 10. In an earth moving device adapted to be moved across the surface of the ground, a draft frame, tiltable earth carrying means on said frame, actuating means engageable with the earth carrying means for tilting same, a hydraulic mechanism connected with said actuating means, said hydraulic mechanism being adapted for connection with a tractive means and shiftable in response to the force exerted by such tractive means, and a cam having oppositely disposed cam surfaces for controlling the travel of the por-

tion of the actuating means which engages said earth carrying means.

In witness whereof, I have hereunto subscribed my name.
